UNITED STATES PATENT OFFICE.

GEORGE M. URIE, OF KANSAS CITY, MISSOURI.

MEMORANDUM ATTACHMENT FOR TELEPHONES.

933,277.

Specification of Letters Patent.

Patented Sept. 7, 1909.

Application filed May 3, 1909. Serial No. 493,616.

To all whom it may concern:

Be it known that I, GEORGE M. URIE, a citizen of the United States, residing at Kansas City, in the county of Jackson and State 5 of Missouri, have invented certain new and useful Improvements in Memorandum Attachments for Telephones; and I do declare the following to be a full, clear, and exact description of the invention, such as will enable others skilled in the art to which it 10 pertains to make and use the same.

This invention relates to improvements in memoranda for telephones.

The object of the invention is to provide 15 an attachment of this character having an improved construction of roll holding bracket for holding the memorandum pad.

A further object is to provide an improved means for holding a carbon sheet 20 for manifolding purposes.

Another object is to provide a memorandum attachment having means thereon to hold a list of subscribers and their telephone numbers.

With the foregoing and other objects in 25 view, the invention consists of certain novel features of construction, combination and arrangement of parts, as will be more fully described and particularly pointed out in 30 the appended claim.

In the accompanying drawings, Figure 1 is a perspective view of the invention, showing the same applied to a telephone; Fig. 2 is an enlarged side view of the attachment, 35 partly in section; Fig. 3 is a top plan view of the attachment; Fig. 4 is a vertical cross sectional view on the line 4-4 of Fig. 3; Fig. 5 is a similar view taken through the carbon paper holders; Fig. 6 is a detail perspective view of one of the carbon paper 40 holders.

In the embodiment of the invention, I provide a base plate 1 which is preferably formed of heavy sheet metal and has its 45 edges turned down to form flanges 2. Secured to the base plate substantially midway between its ends is an attaching bracket 3, consisting of a metal plate, one end of which projects beyond the adjacent edge and said 50 projecting end is provided in its upper edge with a notch 4 to receive the adjacent flange of the base plate, as shown. The bracket 3 is of greater width at its projecting end and said widened end forms a stop to aid in holding 55 the base plate in operative position. The opposite end of the bracket 3 is formed

with a right angularly projecting lug 5 which bears against the inner side of the adjacent flange of the base plate and is riveted or otherwise secured thereto. A similar lug 60 is provided adjacent to the opposite flange of the base plate and is fastened thereto in a similar manner. Secured to the projecting end of the bracket 3 is an attaching clip 6 by means of which the attachment is 65 secured in place on a telephone stand or other support.

On the upper or outer end of the base plate is secured a bail-shaped roll supporting frame 7, in the opposite side members 70 of which are formed vertically disposed slots 8 to receive the trunnions 9 of a roller 10 which is provided to receive the memorandum roll or pad 11. The trunnions 9 are threaded and on the same are screwed clamping nuts 12 by means of which the roll or pad is held in operative position in the frame. The nuts 12 are preferably in the form of concave disks having milled outer edges. 80

Secured to the upper cross piece of the frame 7 is a tension spring 13, one end of which projects down around the outer side of the roll of paper and bears against the same with sufficient pressure to prevent the 85 casual unwinding of the paper therefrom. The spring 13 is preferably secured to the upper cross piece of the frame by means of a clip or loop 14 of metal struck out from the upper cross piece of the frame, as shown. 90 The inner end of the spring projects beyond the inner side of the frame and is preferably bent around into the form of a spring loop or coil to form a pencil holder 15.

Arranged on the base plate 1 adjacent to 95 the inner side of the frame 7 is a pair of carbon paper clamping strips 16. The upper strip is preferably provided with longitudinal grooves 17 to receive the upwardly struck beads 18 formed on the lower strip 100 thus providing an interlocking engagement between the strips to more securely hold the sheet of carbon paper. The ends of the strips 16 are bent downwardly at right angles and are provided with alining notches 105 to receive clamping bolts 19 which are arranged in apertures formed in the side flanges of the base plate, as shown. The bolts 19 are provided on their outer ends with milled heads and on their inner ends 110 with clamping nuts 20 whereby said heads may be drawn into tight engagement with

the right angularly bent ends of the strips to securely clamp the same against the flanges of the base plate and thus hold the sheet of carbon paper in proper position.

5 When the carbon sheet is used, the paper roll will be double-wound and the carbon holding strips and sheet will be arranged between the upper and lower layers of the paper which are drawn over or across the

10 base plate for use. The free ends of the layers of paper are passed beneath and held in position by a guide strip 21 secured to the inner end of the base plate, as shown.

Revolutely mounted between the side members of the frame 7 above the pad or roll 11 is a winding roller 22 upon which is wound a strip of fabric 23 containing the names and telephone numbers of subscribers who are most frequently called for by the user of the

20 telephone. One of the trunnions of the roller 22 projects a suitable distance beyond one side of the frame 7 and on said projecting end of the trunnion is arranged a coiled retracting spring 24, one end of which is

25 secured to the trunnion, while the opposite end is secured in a clip 25 struck out from the adjacent side member of the frame 7. By means of the spring 24, the roller 22 will be caused to rewind the name strip after the

30 same has been pulled out or unwound to ascertain the number of the party wanted.

It will be noted that by means of the pivotal connection of the base plate 1 with the attaching clip 6 that the attachment will

35 readily swing upwardly if engaged with any object so that should the telephone be set down hastily after use and the attachment forcibly struck against an object, that said attachment will yield or swing upwardly thus preventing the same from being

broken off from the stand. The increased width of the bracket 3 at the attaching end of the same forms a stop to engage the side of the telephone stand and thus hold the attachment in operative position.

45

From the foregoing description, taken in connection with the accompanying drawings, the construction and operation of the invention will be readily understood without requiring a more extended explanation.

50

Various changes in the form, proportion and the minor details of construction, may be resorted to without departing from the principle or sacrificing any of the advantages of the invention, as defined in the appended claim.

55

Having thus described my invention, what I claim is:

In an attachment of the character described, a base plate having flanged outer edges, a roll supporting frame secured to said plate, a pad holding roller revolutely mounted in said frame a carbon sheet holder, said holder comprising upper and lower clamping strips having formed therein interlocking beads and grooves, right angularly bent plate engaging ends formed on said strips, said ends having formed therein alining notches, and clamping bolts arranged in said notches and the side flanges of said base plate whereby said strips are fastened in operative position.

60

In testimony whereof I have hereunto set my hand in presence of two subscribing witnesses.

GEORGE M. URIE.
